UNITED STATES PATENT OFFICE.

THEODORE TOLLA AND EDGAR WARREN BOOTS, OF ELLWOOD CITY, PENNSYLVANIA.

AUTOMATIC CUT-OFF FOR GAS LINES.

Application filed May 8, 1922. Serial No. 559,471.

To all whom it may concern:

Be it known that we, THEODORE TOLLA, a citizen of Servia, and EDGAR W. BOOTS, a citizen of the United States, residing at Ellwood City, in the county of Lawrence and State of Pennsylvania, have invented certain new and useful Improvements in an Automatic Cut-Off for Gas Lines; and we do declare the following to be a full, clear, and exact description of the invention, such as will enable others skilled in the art to which it appertains to make and use the same.

This invention relates to an improved device which is adapted to be installed in a gas supply line for cutting off the gas to the burners when the pressure in the supply pipe falls below a predetermined degree, such as would permit the light to be extinguished without warning and thus endangering the life of the occupant of the room in which the gas was escaping unburned.

The principal object of the invention is to generally improve upon a pending and allowed application for an automatic cut-off of this class which bears Serial No. 483,993, and was filed by us on July 11, 1921.

Briefly described, the above named application discloses an automatic cut-off for gas lines which comprises a body having auxiliary and main passages through which the gas is designed to flow separately, both of these passages communicating with an upwardly inclined passage which constitutes a run-way for a ball retainer which is designed to normally co-act with the valve at the upper end of the main passage to maintain it closed. Both the auxiliary and main passages are equipped with independently operable valves for permitting passage of the gas successively through the auxiliary passage first and then through the main passage. The body referred to is composed of a plurality of disconnectible parts as stated and there are separate valves for each of the vertically disposed passages.

As above intimated, it is desirable to improve upon this construction by substituting a body which is in the form of a one-piece metal casting, the same embodying the two vertically disposed main and auxiliary passages and a runway for the ball retainer, but being such in construction as to accommodate a removable bushing which is provided with a valve seat which is employed to permit replacement of this part without requiring removal and substitution of a more ex-

pensive part such as is required with the form of the invention above briefly reviewed.

Another feature of the first invention is to so devise the body as to permit the use of a single two-way automatically operable valve which will immediately open the main passage as soon as the by-pass or auxiliary passage is closed.

Other objects and advantages of the invention will be apparent during the course of the following description.

In the accompanying drawings forming a part of this specification and in which like numerals are employed to designate like parts throughout the same:

Figure 1 is a top plan view of an automatic cut-off constructed in accordance with this invention.

Figure 2 is a front elevational view thereof.

Figure 3 is a side elevation.

Figure 4 is a central vertical sectional view through the improved device showing the position of parts when a full supply of gas is passing through the line.

Figure 4^a is a detail section taken on the line 4^a—4^a of Figure 4.

Figure 5 is a view like Figure 4 showing the position of parts when the gas pressure is insufficient to sustain the check-valve in open position.

Figure 5^a is a detail section of the intermediate part of figure 5 showing the valve turned against the action of the spring to permit passage of the fluid through the bypass.

Figure 6 is a vertical section on the line 6—6 of Figure 4.

Figure 7 is a central vertical section of the removable bushing.

In the drawings, the numeral 1 designates generally a one-piece metal casting or body which includes a vertically disposed tubular main passage 2 provided intermediate its ends with a transversely disposed open ended tapered part 3 which constitutes a housing for a two-way valve or rotary turn plug 4 to be hereinafter more specifically described. The body is designed to provide a by-pass 5 which communicates at its opposite ends with and is disposed in parallelism with the main passage 2. The last named passage is internally screw-threaded at its lower end 6 to permit connection of the supply pipe 6. Communicating with the by-pass and main

passage is an integral upwardly extending tubular part 7 which constitutes what may be conveniently termed run-way for a ball valve retainer 8. The run-way is closed at 5 its outer open end by a removable screw plug 9 which serves to limit the movement of the ball retainer in one direction. Just inward of this closing plug and in one side, the runway is provided with a horizontal 10 discharge port 10 which communicates with an integral angularly disposed pipe-coupling 11. Referring again to the main fluid passage, it will be seen that this is enlarged in diameter intermediate its ends to provide a 15 shoulder 12, and the wall of reduced part of the passage just below the shoulder is screw-threaded to permit a screw-plug 13 to be connected therewith. This plug is provided intermediate its ends with an annular flange 14 20 which rests on the shoulder 12 and it is centrally bored and is equipped with an up-standing tubular extension 15 which constitutes a valve guide which carries a guide pin 16. This screw-plug 13 is threaded into 25 the lower end of a removable bushing or sleeve 17 which is fitted into the enlarged upper portion of the main fluid passage. Adjacent its upper end, the bushing is equipped with relatively small and large openings 18 30 and 19, the first named which communicates with the aforesaid by-pass while the last named one communicates with the aforesaid run-way. The opening 19 is sufficiently large to permit passage of the ball retainer 35 8. Just below these openings, the bushing is equipped with an internal annular rib 20 having a beveled upper face to permit it to function as a valve-seat for a fluid actuated valve 21. This valve is equipped with a depending tubular slotted part 22 into which 40 the upper end of the aforesaid tubular extension 15 telescopes, the pin carried by the latter extending into the slot in this part 22 to prevent rotation of the valve. It is obvious 45 that the ball retainer 8 is designed to rest on the valve 21 to normally retain it closed and to insure effective cooperation of these parts. The valve is provided (as seen clearly in Fig. 6) with guide-groove or seat 50 23. For the purpose of preventing movement of the ball retainer, a screw-plug 24 is threaded into the upper end of the bushing and this plug is adapted to be turned to bind the ball between it and the valve. To facilitate 55 turning of the plug, it is provided with a kerf 25 for reception of the blade of a screw-driver or the like. The plug may be removed for the purpose of gaining access to the ball, valve and its seat. Although it 60 is not essential, the plug 24 is formed in its under face with a guide-groove 26 for co-acting with the first named groove 23. In practice, it is desirable to make use of a removable cap 27 which is threaded on the 65 upper end of the sleeve 17. It may be men-

tioned at this point that the sleeve is formed at this end with diametrically opposite notches 28 to permit use of an ordinary screw-driver in assembling the parts of the device. This particular construction of 70 parts obviates the necessity of using a wrench or special tools in assembling the device, and permits a screw-driver or like implement to suffice during the period of 75 assembling.

Referring again to the rotary turn plug 4, it will be seen that this is equipped at one end with a handle 28 and at its opposite end with a screw-threaded extension 29 passing through the central opening in a washer 30 80 which bears against the small open end of the aforesaid tapered part 3 of the body. A nut 31 is arranged on the free end of the extension 29 and the coiled spring 32 is arranged between the washer and the nut to insure 85 tight contact of the turn-plug with its housing. It is desirable to have this turn-plug normally retained in the position shown in Figures 4 and 5 and to accomplish this end, we simply make use of a coiled 90 spring 33 which is anchored at one end as at 34 on the part 3 of the aforesaid body, being connected at its opposite end with a turn-plug through the medium of a screw 95 35. The part 3 of the body is notched as shown to provide spaced shoulders 36 against which the screw 35 abuts, thus limiting the rotation of the turn-plug in both directions.

The operation of the improved automatic cut-off is as follows: Assuming that the 100 cut-off has been installed in the gas line and that the parts are in the positions clearly disclosed in Figure 5, it will be seen that the gas cannot pass through the line. However, by grasping the handle 28 of the two-way valve 4 and rotating the latter from the position shown in this figure to the one 105 shown in Figure 5^a, it will be seen that the gas will be permitted to pass through the by-pass 5. In so doing, it will pass through the opening 18 and against the ball retainer 8 and will force the latter up the inclined run-way until it comes into contact with the plug 9 at the outer ends of the runway. As 110 soon as the ball retainer has been caused to assume this position, the valve-handle 28 is immediately released and the spring 33 serves to automatically return the valve to its normal position. The gas is then permitted 115 to pass through the main passage 1 and in so doing lifts the valve 20 off of its seat and permits the gas to pass through the runway and into the remaining part of the line through the opening 10 and the coupling 11. If at any time the gas pressure is insufficient 120 to keep the burners lighted, it will be seen that the retainer 8 will roll down the runway and the valve 21 will automatically close by gravity and the ball will roll on top of it to maintain it closed. Hence, the supply 125 130

of gas will be automatically cut off and the lives of the occupants of the house in which the device is installed will not be endangered in any way. Of course, in order to permit 5 the gas to reflow through the line, the above operation must be repeated. It is to be noted that if the pressure is still insufficient when it is desired to turn the gas on again, it will fail to force the ball retainer to its inoperative 10 position in the run-way.

By carefully considering the description in connection with the drawings, persons familiar with devices of this class will doubtless be able to obtain a clear understanding of 15 the invention. Therefore, a more lengthy and detailed description is deemed unnecessary.

Since probably the best results may be obtained with the construction and arrangement herein shown and described, this is 20 taken as the preferred embodiment of the invention. However, we wish it to be understood that minor changes coming within the scope of the invention as claimed may be resorted to if desired.

25 We claim:—

1. An automatic cut-off for gas supply lines comprising a body provided with main and auxiliary passages through which the 30 gas is designed to pass separately and in succession, a valve in said main passage, a run-way communicating with both of said passages, a retainer in the run-way for co-operation with said valve, a rotary turn-plug in said body and having a two-way passage 35 co-operative with said passages, and spring means acting on the valve to automatically maintain it in position so that one of the passages normally communicates with the main passage in the body.

40 2. An automatic cut-off for gas lines comprising a body having a main passage and a by-pass communicating therewith, a valve in said main passage, a removable sleeve also arranged in said passage, the sleeve being provided with a valve seat, a fluid actuated valve cooperative with the seat, and a fluid actuated retainer cooperative with the last named valve.

45 3. An automatic cut-off for gas lines comprising a body having a main passage and a by-pass communicating at its opposite ends with said passage, said body being also equipped with an upwardly inclined tubular extension, a valve in said passage, a sleeve 55 removably arranged in said passage and formed intermediate its ends with an internal valve seat, a fluid actuated valve cooperative with said seat, and a retainer for said fluid actuated valve movable in said run-way.

60 4. In an automatic cut-off for gas lines, a body in the form of a one-piece casting including a vertically disposed tubular part forming a main passage, a by-pass communicating with said passage, and an upwardly inclined and angularly disposed tubular ex-

tension provided at its outer end with a pipe coupling and port opening up communication between the coupling and run-way.

5. The structure set forth in claim 4, together with a transversely disposed tubular 70 open ended part intermediate the ends of the vertically disposed part of the body, said open ended part constituting a housing for a rotary turn plug.

6. In an automatic cut-off for gas supply 75 lines, a removable sleeve provided intermediate its ends with an annular rib having its upper face beveled to provide a valve seat, said sleeve being screw-threaded at its opposite ends and being provided intermediate its ends just above said rib with oppositely disposed relatively small and large 80 openings.

7. In an automatic cut-off for gas supply 85 lines, a removable unit adapted to be disposed in the main passage of a body, said unit comprising a sleeve provided between its ends with a valve seat and adjacent said valve seat with an opening to permit passage of the gas, the sleeve being screw-threaded at its opposite end, plugs threaded into said ends, one of said plugs being centrally bored and equipped with an upstanding tubular guide-extension, and a valve co-operative with said seat and provided with 90 a depending tubular part into which said extension telescopes.

8. The structure set forth in claim 8, together with a pin carried by said upstanding tubular part, said tubular depending part of the valve being formed with a slot 95 through one end, said pin being received in said slot to prevent rotation of the valve with respect to the plug but to permit separation of these parts.

9. In an automatic cut-off for gas supply 100 lines, a sleeve provided between its ends with an internal valve seat, a valve co-operative with said seat, said valve being formed in its upper face with a guide groove, and a plug closing the upper end of said sleeve, the inner face of said plug being formed with a guide groove disposed in spaced parallelism with respect to the 105 first named groove.

10. An automatic cut-off for gas lines 110 comprising a body having a vertically disposed part constituting a main passage, said passage being enlarged in diameter between its ends to provide an internal shoulder, said body being also equipped with a by-pass communicating with said passage at its opposite ends, and being further provided with an angularly disposed upwardly inclined tubular extension providing run-way, 115 said run-way being equipped at its outer ends with a discharge opening, a valve arranged in said body for selectively controlling the passage of fluid through the main 120 passage and by-pass, a removable unit ar- 125

ranged in the enlarged portion of said main passage, said unit including a sleeve having openings communicating with the run-way and by-pass, and being provided with a valve seat below said openings, a valve cooperative with said seat, said valve being gravity lowered, guide means for the valve, and a ball retainer arranged in said run-way

and cooperative with the last named valve to maintain it closed until fluid is passed through the by-pass and brought against it to move it upwardly in the run-way. ¹⁰

In testimony whereof we have hereunto set our hands.

THEODORE TOLLA.
EDGAR WARREN BOOTS.
